STOWAGE OF FUEL TANKS

Hubert Scott-Paine, Hythe, Southampton,
EnglandApplication May 15, 1940, Serial No. 335,268
In Great Britain June 5, 1939

4 Claims. (Cl. 114—0.5)

This invention relates to the stowage of fuel tanks in motor-boats and has for its object to provide an improved construction suitable for use in high-speed motor torpedo boats where large tanks are required. High-speed motor-boats are comparatively lightly built, and in order that they should have a suitable radius of action, the quantity of fuel carried is very large; since it is desirable to keep the weight of the vessel down to a minimum, the tanks also are lightly constructed. It is undesirable to secure the tanks rigidly to the structure of the boat, by brackets and such like fastenings since relative movement may take place which will severely strain the tanks.

According to this invention means for mounting a fuel tank in a high-speed motor-boat comprises a blanket-like packing of felt impregnated with petroleum jelly and covered with canvas surrounding the tank, with one or more rigid bridge-pieces fitting over the packing and tank, and flexible cables which engage said bridge-pieces and are anchored at their ends to the structure of the boat. Preferably, the cables are provided with resilient connections to their anchorages.

When the tank is situated close to a bulkhead or other structural part of the boat, there may also be provided wedging means inserted between the felt packing and the bulkhead.

In the accompanying drawings, which illustrate one embodiment of this invention,

Figure 1 is a transverse sectional view of a boat showing three tanks.

Figure 2 is a partial plan view of Figure 1, and Figure 3 is a part-sectional view on the line 3—3 of Figure 1.

In the particular construction illustrated in the drawings, a whole compartment of a high-speed motor torpedo boat, between forward and after bulkheads, is devoted to fuel tanks which are inserted through a suitably large hatchway in the deck. A flooring 10 of slats is provided on transverse and longitudinal frame-members of the boat to provide a suitably large bearing area on which the tanks stand, and in the form illustrated, three tanks are provided, viz., two wing tanks 11 and 12 and a centre tank 13; the wing tanks are shaped appropriately to fit the sides 14 of the vessel and the centre tank 13 occupies the space between the wing tanks. The tanks extend the full length between the bulkheads of which one is indicated at 15.

A blanket-like packing or lining is provided around each of the tanks as shown at 16, this

packing consisting of a suitable thickness of felt impregnated with petroleum jelly and covered with canvas dressed with a suitable dressing to withstand white ants or other vermin and the like. This packing extends also over the tops of the tanks, being made in pieces of a convenient size to overlap the top as shown in Figure 1.

The tanks are held down on to the flooring by means of rigid channelled members 17 which are shaped to fit over the top of the tank and a suitable distance down each side outside the packing, and a steel cable 18 attached at each end to a spring anchorage 19 on the flooring extends over the tank in this channel. Conveniently a turn-buckle 20 is provided at the top of each tank for the purpose of tightening. Two or more of these channelled members with their cables are disposed transversely of the tank along its length.

The channelled members 17 are sufficiently rigid to prevent any localised stress from the cable being applied to the tank, and the blanket-like packing between the members 17 and the tank further assists in preventing any severe local stress so that the tanks can be securely held in place without subjecting them to undesirable stresses despite the forces to which they are subjected by the movement of the boat as a whole or any small yield which may occur in the structure of the boat.

When the tanks occupy the whole length of a compartment between bulkheads, it is preferred to further restrain them against any movement by wedging them between the bulkheads. This is conveniently effected as shown in Figure 3 where a pair of wedge members 21, 22 are provided between the blanket-like packing 16 on the end of the tank and the bulkhead 15. Preferably these wedges are sufficiently wide to engage substantially the whole end wall of the tank, although it would be appreciated that if the wedge member 21 adjacent the tank is made sufficiently rigid two or more narrow wedges 22 spaced apart could be used with it.

This invention provides a very safe and secure stowage of the fuel tanks which enables tanks of a conveniently light construction to be used and at the same time permits them readily to be removed and replaced when required. The felt packing which is impregnated with petroleum jelly prevents any serious leakage of the tanks should they be accidentally damaged and the whole mounting is sufficiently flexible to allow yield or breathing movements of the hull or the

tanks without stressing or distorting the tanks unduly.

I claim:

1. In a high-speed motor-boat, the combination with a fuel tank of a blanket-like packing of felt impregnated with petroleum jelly surrounding said tank, a rigid bridge-piece constructed and arranged to be fitted over said packing and tank, and flexible means engaged with said bridge-piece anchored at each end to the structure of the boat.

2. In a high-speed motor-boat, the combination of a fuel tank, a blanket-like packing of felt impregnated with petroleum jelly surrounding said tank, a canvas covering on said felt, a rigid member constructed and arranged to extend over said packing and said tank, and a flexible cable engaged with said member and anchored at each end to the structure of the boat.

3. In a high-speed motor-boat, the combination of a fuel tank, a blanket-like packing of felt impregnated with petroleum jelly surrounding said tank, and wedging means constructed and arranged to be interposed between said packing and a bulkhead of the boat.

4. In a high-speed motor-boat, the combination of a fuel tank, a packing of felt impregnated with petroleum jelly covered with canvas enclosing the tops, sides and ends of said tank, a plurality of rigid bridge-pieces constructed and arranged to extend across the said packing and the tops of said tanks, flexible cables engaging each of said bridge-pieces resiliently connected to anchorages on the structure of the boat, and wedging means interposed between the ends of the tank and a bulkhead of the boat.

HUBERT SCOTT-PAINE.
